J. J. KUHN

ACOUSTICAL DEVICE

Filed June 24, 1919

UNITED STATES PATENT OFFICE.

JOHN J. KUHN, OF ELIZABETH, NEW JERSEY, ASSIGNOR TO WESTERN ELECTRIC COMPANY, INCORPORATED, OF NEW YORK, N. Y., A CORPORATION OF NEW YORK.

ACOUSTICAL DEVICE.

Application filed June 24, 1919. Serial No. 306,449.

This invention relates to acoustical devices and more particularly to devices of this character employed in the binaural method of observing and locating sources of vibrations.

In such methods, it is the usual practice to introduce an independent air path between each of a pair of relatively fixed devices for converting the vibrations into observable effects, and the respective ears of the observer. By the proper relative adjustment of the lengths of the two air paths, the difference in time of arrival at each of the affected devices of vibrations propagated from the source under observation may be compensated for so that a binaural balance may be obtained, or in other words, the observer receives the impression that the source is directly ahead when listening binaurally to the observable effects. The angular relation of the source to a base line joining the vibration responsive members of the converting devices may then be determined from an indicating means associated with the compensator which designates the relatively effective lengths of the adjustable air paths.

In order that accurate observations may be made following this method, it is desirable that the air paths of the compensating device shall be acoustically insulated from each other to prevent interference commonly called cross-talk between the observable effects simultaneously passing over such paths.

It is the object of this invention to provide an improved compensating device of this character in which interference between the observable effects in the variable length air tubes is prevented.

To attain this object in accordance with a feature of the invention, the air paths of a compensator employed for this purpose are completely surrounded by metallic walls, thereby eliminating the possibility of any interchange through an air medium of the observable effects in the paths.

This and other features of the invention not specifically mentioned above will clearly appear from the following specification and the annexed drawing, Figs. 1 and 2 of which show a top plan view partially in section and a sectional view of a device embodying the invention, while Figs. 3 and 4 show sectional views of portions of such device taken along the lines 3—3 and 4—4 of Figs. 1 and

2, the portions shown in section in Fig. 1 being taken along the lines 1—1 of Figs. 2, 3 and 4, and Fig. 5 shows diagrammatically the manner in which the device is employed for determining the direction of a source of vibration.

In the drawings, a supporting framework which may be suitably secured to the under side of a suitable table top 1, omitted from Fig. 1 for the sake of clearness, by means of screws passing through holes 3 in a plurality of lugs 4, is provided with a plurality of inwardly extended bridge portions 5 supporting a journal portion 6. The assembled device is preferably enclosed in a suitable casing (not shown) also supported from the under side of the table top 1. A portion 7 projecting downwardly from each of the lugs 4 is provided with a vertical slot 8, an inturned portion of which engages one end of a bent bracket 9, the other end of which is suitably attached to a body member 10 by means of screws 11. A shaft 12 passes through the journal portion 6 of the supporting framework and an aligned clearance aperture in the body portion 10, the upper end of such shaft extending through the table top 1 and provided with a knob or handle 23. The lower plate member 13 is rigidly secured to the shaft 12 by a pin 14 passing through the ferrule 2 of the plate 14 and engaging the shaft 12. Immediately above the body member 10 an upper plate member 15 is rigidly secured to the shaft 12 by means of a key 16 engaging suitable cooperating keyways in a ferrule 17 of the plate 15 and the shaft 12. The upper surface of the journal portion 6 is provided with a lower bearing plate 18 suitably attached thereto and cooperating with ball-bearings 19 introduced between such bearing plate and an upper bearing plate 20 suitably attached to the lower surface of a bushing member 21, rigidly attached to the shaft 12 by means of a pin 22 and to which the knob or handle 23 is attached by means of screws 24. A fixedly positioned stop member 25, upwardly extending from the bent member 9 cooperates with the movable stop pins 26 and 27 suitably attached at predetermined separated locations to upper plate member 15 to limit the rotation in either direction of such plate member and of the simultaneously rotating lower plate member

A telephonic receiver 28 is secured to the upper plate member 15 by a rigid tube 29 projecting from the casing thereof and threadedly engaging a hole 30 through the upper plate member 15. A similar receiver 31 is attached to the lower plate member 13 by a rigid tube 32 threadedly engaging a hole 33 through the lower plate member 13. These receivers are not shown in detail since their exact structure is non-essential to a complete understanding of the invention, any ordinary enclosed type of receiver being suitable, the tubes 29 and 32 being so located in the casings that they convey the sounds produced by the receivers in response to variations in the electrical conditions of associated circuits. Counterweights 34 and 35, suitably attached to the upper plate member 15 and lower plate member 13 respectively, are provided to balance the weights of the associated receivers 28 and 31 respectively, thereby insuring free and uniform rotation of the plate members and maintaining the surfaces of such plate members in proper contact relation with the cooperating surfaces of the body member 10.

The upper surface of the body member 10 is provided with a concentric circular groove 36 preferably of a semi-circular cross-section. The insert member 37, the upper surface of which is flush with the upper surface of the body member 10 and which is secured to the body member by screws 38 extends across the circular groove 36, thereby rendering the groove discontinuous. An elbow-shaped aperture 39 in the body member 10 extends from the groove 36 to the peripheral edge of the body member. The lower surface of the body member 10 is provided with a similar groove 40 which is rendered discontinuous by a flush-mounted insert member 41 secured to the body member in a position directly beneath the member 37. An elbow-shaped aperture 43 in the body member 10, located near the relatively opposite side of member 41 extends from the groove 40 to the peripheral edge of the body member. Bushings 44 and 45, threadedly engaging the body member, provide attachments for equal length tubes 46 and 47, preferably of rubber, leading to usual stethoscopic ear pieces 48 and 49. Closely adjacent one side of the hole 30 through the upper plate member 15, a lug 50 shaped to closely and slidably engage the groove 36 is attached to the plate member 15 by a screw 51, while closely adjacent to the relatively opposite side of the hole 33, a similar lug 52 is attached to the plate member 13 by the screw 53, such lug being located directly beneath the lug 50.

A member 54 attached to the bushing 21 by screws 55 rotates with the shaft 12, and may be provided with a suitably graduated scale observable through the aperture 56 in the table top 1, indicating the degree of rotation

of the shaft and of the simultaneously rotating plates 13 and 15. The arrangement of such scale has been omitted since it is unessential to a clear understanding of the invention.

The operation of the device may be more clearly understood by reference to the diagram of connections, as shown on Fig. 5, from which it will be seen that the sounds produced by receiver 28, are conveyed through the rigid tube 29 and in an anti-clockwise direction when the device is viewed from above, through a portion of the groove 36, the elbow-shaped passage way 39, the co-operating bushing 44 and the tube 46 to the ear piece 48, lug 50 and insert 37 cooperating to determine the effective length of the groove. The sounds produced by the receiver 31 are similarly conveyed through the rigid tube 32 in a clockwise direction through a portion of the groove 40, the elbow-shaped passage way 43, the co-operating bushing 45, and the tube 47 to the ear piece 49, lug 52 and insert 42 cooperating to determine the effective length of the groove.

The observer, listening binaurally to the sounds emanating from the ear pieces 48 and 49 simultaneously receives the sounds produced by the receivers. The handle 23 is then rotated until the impression is received that the source of sound is straight ahead and a reading on the portion of the scale of member 54 exposed through the opening 56 in the table top 1, indicating the relative lengths of the air paths interposed between the receivers and the respective ears of the observer. It will be noted that the lugs 50 and 52 are maintained in vertical alignment during the movement of the simultaneously rotating plate members 13 and 15 so that as the distance through the groove between one lug and the co-operating bushing increases, the similar distance between the other lug and the co-operating bushing decreases a corresponding amount. In this manner, the difference in distances from a source of vibration to the vibration responsive devices, 58 and 59, which control the operating circuits of receivers 28 and 31, respectively may be compensated or binaurally balanced by corresponding differences in the lengths of the air paths interposed between the receivers and the ears of the observer. When this result has been obtained, the observer receives the impression that the source of sound is straight ahead.

Due to the metallic walls completely surrounding the variable air paths of the compensator, the possibility of the transference of sound waves from one path to another through an air medium is prevented, thus eliminating cross-talk and the consequent errors in observation introduced thereby.

What is claimed is:

1. An acoustical device comprising a body

portion, channels formed on the opposite sides thereof, means to close the open sides thereof and means sliding in such channels to vary the effective lengths thereof.

- 5 2. In an acoustical device, a framework, a shaft rotatably supported thereby, a body member rigidly supported by the framework and having a circular groove in each of two surfaces, a plate member carried by the shaft in close relation to each such surface of the body member, means rendering each circular groove discontinuous, and a lug attached to each plate member slidably engaging the groove of the cooperating surface of 10 the body member, said lugs cooperating with the above mentioned means for inversely varying the lengths of portions of the grooves interposed therebetween.
3. In an acoustical device, a framework, 20 a body member rigidly supported thereby and having a concentric circular groove in each of two surfaces thereof, means for rendering each groove discontinuous, an outlet member acoustically connected with each 25 groove, a shaft rotatably supported by the framework, a plate member supported by the shaft and in contact relation with each such surface of the body member, a sound producing device attached to each plate 30 member and acoustically connected to the groove in the adjacent surface of the body member, a stop member attached to each plate member adjacent the sound producing device and slidably engaging the groove in 35 the contacting surface of the body member, said stop members simultaneously causing an inverse and equal variation in the effec-

tive lengths of the grooves from the sound producing devices to the outlet members during the rotation of the shaft, and means 40 carried by each plate cooperating with the associated sound producing device to maintain the contact relation between the plate members and the associated surfaces of the body member. 45

4. In an acoustical device, a framework, a body member rigidly supported thereby and having a concentric circular groove in each of two surfaces thereof, a stop member inserted in each such surface to render each groove discontinuous, a stethoscopic tube acoustically connected to each groove through the body portion, said tubes being located on relatively opposite sides of the associated stop members, a shaft rotatably supported by the framework, a plate member carried by the shaft and in contact relation with each surface of the body member, a stop member carried by each plate and slidably engaging the groove in the contacting surface of the body portion, and a sound producing device acoustically connected with each groove through the contacting plate member on relatively opposite sides of the stop member, said stop members operating during the rotation of the plate members to simultaneously cause an inverse and equal variation in the effective lengths of the grooves interposed between the sound producing devices and the stethoscopic tubes. 50 55 60 65 70

In witness whereof, I hereunto subscribe my name this 18th day of June, A. D., 1919.

JOHN J. KUHN.
